UNITED STATES PATENT OFFICE.

JOHN M. ATKINSON, OF CHICAGO, ILLINOIS, ASSIGNOR, BY MESNE ASSIGNMENTS, TO THE RAIL JOINT COMPANY, A CORPORATION OF NEW YORK.

MEANS FOR ELECTRICALLY CONNECTING RAILWAY-RAILS AND THE LIKE.

No. 813,996.

Specification of Letters Patent.

Patented Feb. 27, 1906.

Application filed March 16, 1904. Serial No. 198,302.

To all whom it may concern:

Be it known that I, JOHN M. ATKINSON, a citizen of the United States, residing at Chicago, Cook county, Illinois, have invented 5 certain new and useful Improvements in Means for Electrically Connecting Railway-Rails and the Like, of which the following is a complete specification.

This invention relates to means for electrically connecting railway-rails and the like to form a return-circuit for the electrical current of electric railways, and relates particularly to the type of connection or bond shown and described in United States Letters Patent

15 No. 697,534, dated April 15, 1902.

The object of the invention is to provide a more perfect electrical connection between the rails and the plates or angle-bars which connect the rails than can be secured by the present means of forming such connections.

To this end my invention consists in the use of an electrical conductor having an actual molecular contact with the angle bars or plates which connect the rails as distinguished from what may be termed the mere "laid-on" contact produced by inserting a separate conductor-strip between members of the rail-joint, as described in the patent above referred to.

The invention also consists of the various other features, combinations of features, and details of construction hereinafter described and claimed.

In the accompanying drawings a rail-joint 5 with electric connections embodying my invention is fully illustrated.

Figure 1 is a side view of a rail-joint comprising an electric bond or connection of my invention. Fig. 2 is a sectional view thereof on the line $x-x$ of Fig. 1, and Fig. 3 is a partial perspective view of one of the connecting-bars forming the rail-joint before the electrical conductor is deposited thereon.

Referring now to the drawings, 1 designates 5 the rails of a railway-track, 2 the connecting-plates or angle-bars which connect adjacent ends of said rails, and 3 bolts which clamp said rails and angle-bars together. The foregoing parts are shown merely for the purpose of illustrating a concrete embodiment of my invention, and as regards their general features may be of any usual or desired construction. Also while I have shown but a

single form of angle-bar the form shown is merely typical, and any other desired form of 55 connecting member, either angle-bar or fish-plate, may be substituted therefor without in any way departing from my invention. As shown, the electrical conductor 4 is applied to the angle-bars 2 in such position that it 60 will contact with the upper surfaces of the rail-bases 5 when the members of the rail-joint are assembled. My invention, however, contemplates applying said electrical conductor 4 between any other opposed surfaces of the rail-joint members, as indicated in dotted lines at 4^a.

Instead of inserting the conductor 4 between the rails 1 and the angle-plates 2 in the form of detached strips, said conductor is applied in such manner as to secure an actual molecular contact thereof with either or both of the opposed joint members, being permanently secured thereto and forming, in effect, an integral portion thereof. This intimate 75 molecular contact or association of the electrical conductor with the members of the rail-joint may be effected by electrodepositing a coating or layer of any desired conductor of 80 electricity, preferably copper, in proper position upon members of the rail-joint, which can be effected either by chemical or electrolytic action in a familiar manner.

As shown, the conductor 4 is electrodeposited in a seat or recess 6, formed in the angle-bar, said electrodeposit being preferably slightly thicker than the depth of said seat or recess 6, thereby insuring a firm contact between said conductor and the opposed surfaces of the rail. I do not desire, however, to 90 limit myself either as to the shape, thickness, or manner in which said electrolytically-deposited conductor is applied.

While electrical rail bonds or connections of the type shown in said Patent No. 697,534 95 are much more efficient than the forms of bonds previously in use, they are open to the objection that the scale or oxidized surface of the members of the rail-joint increases the resistance to the passage of the electrical current between said rail-joint members and the conductor-strips. While this objectionable feature might be overcome to a large extent by properly dressing the surfaces of the rail-joint members with which the conductor contacts, it is impossible to provide against the 100 105

carelessness of workmen and mechanics, the result being that many imperfect joints would result. A particular advantage arising from the use of an electrodeposited as distinguished from a laid-on conductor-strip is that in order to secure the requisite chemical reaction for depositing the conducting material the surfaces of the rail-joint members designed to receive said electrodeposit must not only be dressed to remove the scale or oxidized surface, but must also be thoroughly cleansed of all foreign matter, grease, and the like before the desired deposit will take place. It is thus obvious that the molecules of the electrolytically-deposited conductor will be as intimately associated with the exposed molecules of the rail-joint member or members on which it is deposited as are the molecules of the electrodeposit with each other. In this manner a much more perfect electrical connection is effected and the resistance of the connection accordingly reduced. Furthermore, by the construction above described I provide an angle-bar as an article of manufacture and sale, which embodies in itself a conductive part which is not loose and liable to become detached and lost in the market or while in the storehouse, but is al-

ways in place ready for very efficient service in connection with a railway-rail. 30

I claim as my invention—

1. The improved angle-bar for connecting railway-rails, comprising an angle-bar having a shallow recess formed in a bearing of said angle-bar adapted to engage the rail, said recess containing a high conductor of electricity deposited in permanent molecular connection with the comparatively low conductive body of metal of said angle-bar. 35

2. The combination with the railway-rails, 40 of angle-bars for connecting said railway-rails, said bars comprising angular, conducting-bars formed to contact with the faces of the rail-bases, the contact-bearings being recessed and containing a molecularly-adhering electrodeposit of highly-conductive metal adapted to contact with said flange of the rail, substantially as set forth. 45

In testimony that I claim the foregoing as my invention I affix my signature, in presence 50 of two subscribing witnesses, this 23d day of February, A. D. 1904.

JOHN M. ATKINSON.
